UNITED STATES PATENT OFFICE.

JOHN SEBASTIAN WEAVER AND JOSEPH BERNARD WEAVER, OF NEW OXFORD,
PENNSYLVANIA.

TROUGH.

No. 927,197.

Specification of Letters Patent.

Patented July 6, 1909.

Application filed August 27, 1908. Serial No. 450,427.

To all whom it may concern:

Be it known that we, JOHN S. WEAVER and JOSEPH B. WEAVER, citizens of the United States, and residents of New Oxford, 5 in the county of Adams and State of Pennsylvania, have invented a new and Improved Trough, of which the following is a full, clear, and exact description.

This invention is an improvement in troughs such as are generally used for feeding and watering stock, and has in view a trough such that the ends may be easily applied to and detached from the body and form water-tight connections therewith, 10 whereby the parts when disassembled can be closely packed, convenient for shipment and stowage. To this end we preferably provide the ends of the trough with inwardly-projecting curved flanges which receive the opposite ends of the trough body and are firmly 15 pressed or clamped thereto by bowed members arranged inside of the body over the respective flanges and compressed at opposite ends, a gasket being inserted at the joint 20 thus made, to insure a water-tight connection.

Reference is to be had to the accompanying drawings forming a part of this specification, in which similar characters of reference 25 indicate corresponding parts in all the views.

Figure 1 is a perspective view of a trough constructed in accordance with our invention; Fig. 2 is a fragmentary vertical sectional view substantially on the line 2—2 of Fig. 1; and Fig. 3 is a cross-section of the trough through the body thereof.

The trough is essentially composed of three primary parts, which are the body 5 40 and the ends 6, 6, the latter being constructed with supporting feet 7, and inwardly-projecting flanges 8, the said flanges having a form and size corresponding to that of the body 5, thus making the flange of each end 45 consist of an approximately semi-circular bottom portion and a straight top portion. On the curved portions of the flanges 8 of the ends of the trough are seated the opposite ends of the body 5, and placed over these 50 flanges within the body, and of like form,

are bowed members 9, preferably semi-circular in cross-section, with the ends of each terminating near the under face of the straight top flange. Each member 9 is compressed at the ends by set-screws 10 threaded 55 through the straight top flange, thus forcing the body of the trough toward the bottom curved flanges.

In order that the joint made between the body of the trough and each end may be 60 water-tight, we provide in connection therewith a gasket 11 which is preferably interposed between the curved flanges and body, as illustrated in Figs. 2 and 3.

The lateral outward pressure of the bowed 65 members at their upper portions, as well as that of the body 5, may be augmented by making the members and body of slightly greater width across the top than the inside diameter of the curved flange, before the 70 parts of the trough are assembled. In this way when the trough is set up, both the body and the members 9 will tend to spread out toward the curved flanges and thus make the joint tight at the top. A trough thus 75 constructed may be readily set up and dismounted, in which latter condition it is adapted to be packed within a relatively small space convenient for shipment or storage. 80

Having thus described our invention, we claim as new and desire to secure by Letters Patent:

1. The combination of trough ends having inwardly-projecting curved flanges, a trough body having its opposite ends conforming to said flanges and seated thereon, bowed members arranged inside of the trough body over the flanges, said trough ends having portions arranged over the ends of the bowed members, and set-screws threaded into said portions and bearing on the ends of the bowed members. 85 90

2. The combination of trough ends having supporting feet and provided with inwardly-projecting flanges, the flange of each end having a curved lower portion and a straight upper portion, a trough body having its opposite ends seated on the flanges of the ends and conforming thereto, bowed mem- 95 100

bers arranged within the body over the curved portions of the flanges of the trough ends, and set-screws threaded through the straight portion of the flange of each trough 5 end and bearing on the ends of the adjacent bowed member.

In testimony whereof we have signed our

names to this specification in the presence of two subscribing witnesses.

JOHN SEBASTIAN WEAVER.
JOSEPH BERNARD WEAVER.
